DESIGN FOR A FLOWERPOT

Joseph Wright, New York, N. Y.

Application July 6, 1935, Serial No. 57,540

Term of patent 7 years

To all whom it may concern:

Be it known that I, Joseph Wright, a citizen of the United States and a resident of the city of New York, Borough of the Bronx, in the county of Bronx and State of New York, have invented a new, original, and ornamental Design for a Flowerpot, of which the following is a specification, reference being had to the accompanying drawing, forming part thereof, in which

Figures 1 and 2 are, respectively, perspective views of a flowerpot taken from different angles, showing my new design.

The dominant feature of my design consists of the dots and their scattered arrangement and contrasting color to the body of the flowerpot.

I claim:

The ornamental design for a flowerpot, substantially as shown and described.

JOSEPH WRIGHT.
